DISPLAY SIGN

Filed Jan. 28, 1930

UNITED STATES PATENT OFFICE

CHARLES L. LEWIS, OF MONROVIA, CALIFORNIA

DISPLAY SIGN

Application filed January 28, 1930. Serial No. 423,991.

This invention relates to a display sign particularly applicable to fruit and vegetable stores where it is desired to display the name and the cost of piles of fruits or vegetables. 5 The present method is to paint a card, place it upon a stick and insert this stick into the pile of fruit or vegetables, or else secure the card to the stall or container.

An object of my invention is to provide a 10 display sign which conforms approximately to the shape of the fruit or vegetables so that it may be placed on the pile or stack without injuring any of the fruits or vegetables, and which will also be pleasing in 15 appearance.

Another object is to provide a sign of the character stated which will not, in any way, injure the fruit or vegetables upon which it is placed.

20 Still another object is to provide a movable dial or curtain so that the names of various fruits or vegetables, and the prices thereof, can be displayed one at a time on my device. The curtain being so arranged that it can be 25 rotated to display any of the names or prices thereon.

A further object is to provide a sign of the character stated which is simple in construction, which is pleasing in appearance, 30 and which is effective in use.

Other objects, advantages, and features of invention may appear from the accompanying drawings, the subjoined detailed description and the appended claims.

35 In the drawings

Figure 1 is a plan view of my sign.

Figure 2 is a side elevation of the same with parts broken away to show interior construction.

40 Figure 3 is a side elevation of one-half of the sign.

Figure 4 is a fragmentary, sectional view of the case, showing the method of attaching the two parts together.

45 Referring more particularly to the drawings, my display sign is formed in two complementary halves 1-2. These halves are in the nature of a shell and formed of a metal or fiber which can readily be molded or stamped

50 and then painted or nickelized to form a pleas-

ing appearance. The halves 1-2, when placed together form a partial sphere so that the sign can be placed in a pile of fruit or vegetables and will remain in place because of its shape rather than because of any sharp 55 or protruding portions.

In one of the halves I provide a movable curtain 3 upon which is imprinted the names of various fruits or vegetables. As here shown, this curtain is placed in the section 1. 60 In the complementary section 2, I provide a curtain 4 which has imprinted upon it various prices representing the sales price of the fruit or vegetable appearing on the curtain in the other section, an example being shown 65 in Figure 1. An opening 5 is provided in the top of the section 1 through which the name of the fruit or vegetable appears, and a similar opening 6 is provided in the section 2 through which the printing on the curtain 70 4 appears. The sections 1-2 are flattened as at A-B so that a plane surface is provided when the two sections are joined together substantially as shown.

An idler drum 7 is journaled on a shaft 8 75 adjacent the upper end of the section 1, and the curtain 3 extends over this drum. Two shafts 9-10 are journaled in the section 1 below the shaft 8. One end of the curtain 3 is secured to each of the shafts 9-10. The 80 shafts are preferably split and the curtain is threaded through this split in the shaft. The curtain 4 is mounted in the identical manner as described for the curtain 3. An idler drum 11 is journaled adjacent the upper end of the section 2 below the sight opening 6. A pair of shafts 12-13 are journaled in the section below the drum 11, and either end of the curtain 3 is secured to these shafts in the same manner as previously described 85 for the curtain 3. The shafts 9-10-12-13 are each provided with a knurled button 14 on one end thereof, and another knurled button 15 on the other end thereof. By means of the knurled buttons 14-15, the shafts can 90 be rotated to move the curtains 3-4 so that the desired subject matter appears in the sight openings 5-6.

The two halves of the sign are preferably held together by plates 16-17, one on either 100

side of the sign. Said plates extending between the halves, and screws 18—19 extend through each of the plates into the halves 1—2.

5 Having described my invention, I claim:

1. A display sign comprising a shell, said shell being formed in two complementary halves, and said shell being substantially spherical in shape, a curtain in each of said halves, each of said halves having a sight opening in the top thereof and manual means to move said curtain whereby various signs on the curtains are displayed in the sight openings.

15 2. A display sign comprising a shell, said shell being formed in two complementary halves, means removably securing said complementary halves together, each of said halves having a sight opening in the top thereof, a curtain in each of said halves, a drum journaled in each of said halves over which the curtain extends, and two shafts journaled in each of said halves, said curtain being secured at either end to said shafts.

25 3. A display sign comprising a shell, said shell being formed in two complementary halves, means removably securing said complementary halves together, each of said halves having a sight opening in the top thereof, a curtain in each of said halves, a drum journaled in each of said halves over which the curtain extends, and two shafts journaled in each of said halves, said curtain being secured at either end to said shafts, 35 and knurled buttons secured to both ends of each of said shafts whereby said shafts may be manually rotated.

In testimony whereof, I affix my signature.

CHARLES L. LEWIS.
